UNITED STATES PATENT OFFICE.

JOHN DOUGLAS, OF EAST SHEEN, SURREY, ENGLAND.

INTERNAL-COMBUSTION ENGINE.

1,109,518.

Specification of Letters Patent.

Patented Sept. 1, 1914.

Application filed November 23, 1912. Serial No. 733,113.

To all whom it may concern:

Be it known that I, JOHN DOUGLAS, a subject of the King of England, residing in East Sheen, Surrey, England, have invented 5 certain new and useful Improvements in Internal-Combustion Engines, of which the following is a specification.

This invention relates to internal combustion engines.

10 One of the important objects of the present invention is to reduce the weight for power developed of internal combustion engines having either stationary cylinders or rotating cylinders.

15 The present invention relates to the type of internal combustion motor wherein two pistons are employed, one of which is hollow and works within the cylinder and the other works within the hollow piston, the space 20 between the two pistons being employed as a pump-chamber to compress mixture and pass it to that end of the cylinder from which the hollow piston starts when making its working stroke.

25 The invention will be described as applied to an engine of this type having the following well-known features:—The hollow piston has an extension that works in an extension of the cylinder and at that end of 30

the piston-extension are ports which communicate with other ports at the end of the cylinder-extension toward the completion of the compression stroke and are uncovered in the cylinder itself when the piston is approximately at the end of its working stroke.

35 A charge can thus be compressed between the hollow piston and the other piston within it and then passed under pressure through the piston-extension into the working portion

40 of the cylinder, the part provided between the two pistons constituting a pump-chamber. The charge is admitted to the pump-chamber through the ports at the end

45 of the cylinder-extension when those in the piston-extension are brought to register with them, and escapes from the pump-chamber to the working portion of the cylinder when the ports in the piston-extension are brought into such working portion.

50 According to the present invention, the engine which is of the type described and may or may not have the other well-known features referred to, is characterized by the pump-chamber between the pistons being provided with ports near one end for ad-

mitting air only and elsewhere with ports for admitting mixture, so that the pure air is kept at one end and can be discharged first into the combustion chamber for scavenging. Preferably the pump-chamber is arranged to compress a larger charge than is required for the cylinder, so that when a portion has been employed, for scavenging, a full charge at the proper pressure still remains in the cylinder. This feature in itself is not new, but is useful in conjunction with other features of the engine constituting the subject-matter of the present invention.

The invention further relates to constructional details hereinafter fully described with reference to the drawings and whereof the novel features are pointed out in the claims.

In the accompanying drawings:—Figure 1 is an elevation in part section of an engine with stationary cylinders; Fig. 2 shows a part of Fig. 1 on a larger scale; Fig. 3 is a diagrammatic view of a detail; Fig. 4 is a side elevation of an engine having rotating cylinders, and Fig. 5 is a section through the same on the line 5—5 of Fig. 4.

Like letters indicate like parts throughout the drawings.

The engine shown in Fig. 1 is provided with two cylinders A, A¹, supported by crank-chambers A², A³ which are conveniently square in plan having openings back and front closed by plates whereof one is shown at A⁴ partly broken away for clearness. The cylinder A with its parts is shown in central vertical section, but the cylinder A¹ with its parts is shown in elevation. Each cylinder is surrounded by a square jacket A⁵ providing water-spaces A⁶ and having openings at the sides closed by cover plates A⁷.

The two cylinders and their respective parts are exactly alike so that for convenience the further description may be confined to the cylinder A. This has top and bottom extensions B and C respectively, the top one, B, of which is conveniently closed at its end. Within the cylinder is a hollow piston (Fig. 1) composed of three parts, a central part D and two end portions D¹. The central portion D has its ends turned over as at d and the annular channel thus provided at each end is made to receive the heads of bolts d¹, the other ends whereof pass through shoulders on the end portions D¹ and receive nuts 115

d^2 . This construction permits of the introduction of packing-pieces d^3 between the central portion D and end-portions D¹ that are useful for adjustment purposes as hereininafter described. Around the overturned ends of the central part D and around the working faces of the end-portions D¹ packing-rings d^4 of convenient construction are placed. The wall of the central portion D of the piston is provided with a series of perforations or ports D² that are disposed in a plane transverse to the longitudinal axis of the piston and situated approximately midway of the length of the same.

15 The hollow piston has on each portion D¹ a hollow extension D³ which is closed at its end and has a sliding fit within the cylinder extensions B and C respectively. The end of each extension carries two sets of packing rings D⁴ that are separated by a series of ports D⁵ in the piston extension. Each cylinder extension also has a set of ports B¹ C¹ respectively that register with the ports D⁵ when the piston-extension is fully advanced 25 into the corresponding cylinder-extension. The ports B¹ communicate with a channel B² that has communication with the atmosphere through the inlet port B³ (see cylinder A¹) and the ports C¹ similarly correspond 30 with an annular channel C² which has communication with the atmosphere by means of a port C³ (see cylinder A¹). The piston-extension D³ that is toward the crank-shaft E carries beyond the piston-rings D⁴ and 35 ports D⁵, a gudgeon-pin D⁶ for a connecting rod E¹ that extends out beyond the piston and cylinder extensions and engages a crank E³ on the engine crank-shaft E.

40 Co-axially within the hollow piston is mounted a closed piston F connected by a central rod F¹ to a yoke F². The yoke is disposed beyond the end of that extension of the cylinder remote from the crank-shaft and the rod F¹ passes through the closed end 45 of the piston-extension and the corresponding closed end of the cylinder-extension to enable it to be secured to the yoke F². The arms of the yoke have secured to them rods F³, one on each side of the engine cylinder, 50 which pass down the sides and through cored portions of the cylinder wall. At the crank-shaft ends they are received in guides F⁴. The cylinder covers are secured by studs and nuts A⁸, A⁹ respectively and two 55 of these at the top and two corresponding studs at the bottom are made hollow to accommodate the rods F³ which thus extend right through them. These studs A⁸ thus constitute additional guides for the rods F³.

60 The crank-shaft ends of the rods carry pins F⁵ that receive the ends of eccentric rods F⁶. These rods are connected to eccentric straps F⁷ that surround eccentrics E² on the crank-shaft E. These eccentrics are disposed at an 65 angle of 180° to the crank E³ that is en-

gaged by the connecting rod E¹ of the hollow piston and are set one on each side of the same.

Each cylinder A and A¹ has cast around it three enlargements A¹⁰, A¹¹, and A¹² respectively. These enlargements are hollow and communicating with them and the interior of the cylinder are ports A¹³, A¹⁴ and A¹⁵ respectively. Each port is cut through the wall by a boring-tool so that it takes the form of a continuous slot right around the interior of the cylinder, and the cylinder is strengthened at these parts by ribs A¹⁶ which are cast in such position that when the slot is cut they constitute bridge-pieces 75 across the ports and serve to give the necessary strength to the cylinder.

The interior of the hollow enlargement A¹⁰ communicates with an exhaust passage G, the interior of the hollow enlargement A¹¹ communicates with a passage G¹ that has connection with the carbureter and if desired with a suitable additional air inlet for providing an explosive mixture, and the hollow enlargement A¹² communicates with 90 a second exhaust passage G² which may be connected with the exhaust passage G if desired.

The engine thus described is double-acting and works on the two-stroke cycle. With the parts in the position shown in the left-hand portion of Fig. 1, that is to say, the cylinder A and its pistons, it may be assumed that the combustion chamber H which is at the upper end of one working portion of the cylinder A, contains an explosive charge under pressure ready to be ignited, and the pump-chamber, that is to say, the space within the hollow piston that lies above the piston F, is charged in the main 100 with mixture, but the upper portion with pure air only. If the charge in the combustion chamber is now exploded, the hollow piston, D, D¹ is forced downward on its working stroke and operates the crank-shaft, the eccentrics E² simultaneously moving the piston F upwardly. At the first movement the ports D² and D⁵ are closed, the ports D² by being covered by the piston F and the ports D⁵ by being moved down 105 out of register with the ports B¹; the charge in the pump chamber is thus compressed. Toward the end of the working stroke the ports A¹³ are uncovered by the shoulder of the hollow piston so that exhaust commences 110 into the hollow enlargement A¹⁰ and thence to the passage G and shortly after the commencement of exhaust, the ports D⁵ are brought down below the extension B of the cylinder so that they register with the combustion chamber or working portion of the cylinder. The charge compressed within the hollow piston can thus escape into the working portion of the cylinder through the ports D⁵ and in doing so the upper portion 115

of the charge which is pure air only passes rapidly through the cylinder and makes its escape by the exhaust ports, sweeping the remainder of the exhaust out with it. The parts are then in the position shown in the lower portion of the cylinder A¹ where exhaust is taking place on the opposite side of the piston F and the movement of the two pistons is now reversed so that they begin to recede from each other, the ports D⁵ being immediately closed by their being carried again into the extension B of the cylinder and the ports D² being covered by the piston F. Suction is thus created within the hollow piston until the ports D² are uncovered when explosive mixture will be sucked in from the passage G¹ through the ports A¹⁴ of the hollow enlargement of the cylinder and the ports D². By the upward travel of the hollow piston the ports D⁵ are again brought to register with the ports B¹ in the cylinder extension B and thus pure air is sucked in through the port B² with which the ports B¹ communicate. This air lies at the top of the explosive charge in the hollow piston and does not get mixed with such charge to any appreciable extent. During the upward movement of the hollow piston the charge formerly introduced into the working portion of the cylinder has been compressed into the combustion chamber H, and the parts are once more in the position assumed at the commencement of operations, so that the cycle of operations is now repeated.

It will be understood that the engine being double-acting, the same cycle of events is taking place in the lower portion of the cylinder A whose piston performs its working stroke alternately with the upper portion of the cylinder. It will be seen that the movement of the pistons D, D¹ and F in opposite phase, enable the pump-chamber to be made of greater capacity than the working-portion of the cylinder A, so that a surplus portion of the charge in the pump-chamber can be discharged for scavenging, such surplus portion preferably consisting of air only, and that the ports D⁵ serve to admit this surplus charge of air and also to discharge the contents of the pump-chamber into the working portion of the cylinder.

By providing suitable controlling valves for the port B² and passage G¹ and connecting these to a single operating member, the amount of pure air admitted may be varied at will in proportion to variations made in the amount of mixture admitted. Thus, in Fig. 3 a valve J controls the inlet B³ to the port B², and a valve J¹ is provided in a conduit G³ connecting the carbureter and air inlet with the passage G¹ to admit mixture. If then the two valves J, J¹ are connected by a rack engaging with pinions on the valve spindles, movement of the rack will

move both the valves simultaneously and by properly proportioning the passage-ways through the valves and by initially setting the valves in connection with the rack at what is the proper proportion for full working, the mixture may be throttled and more air proportionately introduced until if desired, the mixture can be cut off altogether and air only circulated in and out of the engine.

The object of the packing-pieces d³ between the piston parts D, D¹ is to permit of adjustment of these parts so that they can be arranged to cover or uncover the ports A¹³, A¹⁴ and A¹⁵, exactly at the required moment; moreover, these ports being arranged to be cut by a boring tool can be positioned far more accurately than is possible where the ports are cast in the cylinder.

It should be observed that the mass movement of the piston F, with its appropriate parts, is made to balance the mass movement of the hollow piston D, D¹ with its appropriate parts, and these working in opposite phase, give a balanced engine.

Obviously many modifications may be made in this engine as to the arrangement of the ports and various details of the engine: thus for example the upper extension B of the cylinder and the passages B² and G with their ports could be omitted and the engine operated as a single acting engine using only the lower combustion chamber; but such and other modifications are common engineering practice and can be made without departing from the spirit of the invention.

In Figs. 4 and 5 an engine is shown that operates upon the same principle as that shown in Figs. 1-3, but the cylinders are arranged to rotate and the pistons instead of being one inside the other, both have sliding contact with the cylinder although one has an extension that can pass through the other; moreover the engine shown is a single acting one. Each cylinder K has mounted in it two pistons L, L¹ respectively. The piston L has a hollow extension L² that is closed at its end by a suction valve L³ and between the valve and the cylinder, ports L⁴ are provided in the extension. The tubular extension L² communicates by ports L⁵ with the pump-chamber M that is provided between the pistons L, L¹ and these ports L⁵ are formed in a centrally disposed tubular stem L⁶ that is connected to the piston L but is closed by a partition L⁷. Within the tubular stem and between the partition L⁷ and the crank-shaft, a gudgeon pin is mounted to receive a connecting rod N that communicates the motion of the piston to a crank N¹ on a crank-shaft N². The piston L¹ is hollow and has an open neck L⁸ through which the tubular stem L⁶ of the piston L can pass. Pivoted within the piston L¹ on that side toward the crank-shaft

are two connecting-rods N^3 , one on each side of the rod N and these are operatively connected with cranks N^4 set at 180° to the crank N^1 .

- 5 The explosive mixture is admitted to the crank-case through a passage-way N^5 in the crank-shaft and enters the pump-chamber through ports M^1 in a portion of the wall of the cylinder K that projects into the 10 crank-case. The cycle of operations is the same as that already described with reference to the engine shown in Figs. 1—3 and exhaust takes place through ports M^2 in the cylinder M when these are uncovered by the 15 piston L . The amount of air admitted to the pump-chamber may be varied by adjusting the spring of the suction valve L^3 to resist opening more or less strongly according to whether less or more air is required.
- 20 The engine shown is provided with seven cylinders the various pistons and connecting-rods of which all operate on to the one set of cranks, as clearly shown in the drawings. Obviously a greater or smaller number of cylinders may be provided according to requirements.

What I claim as my invention and desire to secure by Letters Patent is:—

1. In an internal combustion engine the 30 combination of a cylinder, a working piston reciprocating therein, said piston constituting one wall of the combustion chamber between it and the end of the cylinder, a second piston reciprocating in said cylinder and 35 moving relatively to said first piston, an inlet port admitting a charge into the space between the two pistons, said space between the pistons being so proportioned relatively to the working portion of the cylinder that 40 a larger charge can be compressed therein than is necessary to fill the working portion of the cylinder at a suitable pressure whereby the surplus is available for scavenging without the pressure of the charge retained 45 being reduced below the normal, and means for admitting the charge so compressed between the pistons into the working portion of the cylinder wherein said first piston operates.

- 50 2. In an internal combustion engine the

combination of, a cylinder, two pistons reciprocating therein and moving relatively to one another, the space between the two pistons being so proportioned relatively to the working portion of said cylinder that a 55 larger charge can be compressed therein than is necessary to fill said working portion of the cylinder at a suitable pressure, an air inlet at one end and a mixture inlet at the other end of said space between the pistons, transfer ports connecting said space and said working portion of the cylinder whereby the air and mixture are discharged separately thereinto and whereby only a portion of the pure air is permitted to escape. 60

3. An internal combustion engine comprising a cylinder formed with an extension or neck at the end adjacent to the crank shaft, a hollow piston provided with a hollow extension projecting through said cylinder extension adapted to carry the gudgeon-pin to connect with said shaft; a second piston within said piston carried by a rod extending through the other end of said cylinder remote from the crank-shaft, a yoke for 75 said rod, guide rods for said yoke extending downwardly on each side of the cylinder to connect with the crank-shaft.

4. An internal combustion engine comprising a cylinder formed with an extension 80 having ports therein, a hollow piston provided with an extension for said cylinder, a piston within said hollow piston forming a pump-chamber, ports in said piston extension adapted to alternately register with 85 the working portion of the cylinder, whereby air is admitted to said pump-chamber, ports in said hollow piston adapted to be shut and opened by said second piston, said ports communicating with a chamber, ports 90 in the cylinder wall communicating with said chamber.

In testimony whereof I have signed my 95 ports in said cylinder extension and with name to this specification in the presence of two subscribing witnesses.

JOHN DOUGLAS.
